[57] CLAIM

The ornamental design for a goblet or similar article, as
shown and described.

DESCRIPTION

FIG. 1 is an elevational view of a goblet or similar
article showing my new design;

FIG. 2 is a top plan view thereof;

FIG. 3 is a top perspective view thereof;

FIG. 4 is a bottom plan view thereof;

FIG. 5 is an elevational view of a first modification of
my design of FIG. 1;

FIG. 6 is a top plan view thereof;

FIG. 7 is an elevational view of a second modification
of my design of FIG. 1;

FIG. 8 is a top plan view thereof;

FIG. 9 is an elevational view of a third modification of
my design of FIG. 1;

FIG. 10 is a top plan view thereof;

FIG. 11 is an elevational view of a fourth modification
of my design of FIG. 1; and

FIG. 12 is a top plan view thereof.

Bottom plan views of the design of FIGS. 5, 7, 9 and 11
would be substantially similar to FIG. 4 with variations
in proportions being understood from the existing
views.Fig.1
